UNITED STATES PATENT OFFICE.

AXEL ANSHELM CARLSON, OF LINDSBORG, KANSAS.

SAFETY-RAZOR.

1,007,847.

Specification of Letters Patent.

Patented Nov. 7, 1911.

Application filed October 17, 1910. Serial No. 587,485.

To all whom it may concern:

Be it known that I, AXEL ANSHELM, CARLSON, a citizen of the United States, residing at Lindsborg, in the county of McPherson and State of Kansas, have invented certain new and useful Improvements in Safety-Razors; and I do declare the following to be a full, clear, and exact description of the invention, such as will enable others skilled in the art to which it appertains to make and use the same.

This invention relates to an improved safety razor.

The object of the invention is to provide a simply constructed razor of this class having a plurality of blades arranged in position ready for successive use and having adjustable means for holding one blade at a time in operative position.

With this and other objects in view, the invention consists of certain novel features of construction, combination and arrangement of parts as will be more fully described and particularly pointed out in the appended claims.

In the accompanying drawings; Figure 1 is an end elevation of this improved razor; Fig. 2 is a front elevation thereof; Fig. 3 is a longitudinal vertical section thereof; Fig. 4 is a transverse vertical section thereof; Fig. 5 is a similar view taken on the line 5—5 of Fig. 3; Fig. 6 is a horizontal section taken on the line 6—6 of Fig. 4.

In the embodiment illustrated, a casing 1 is shown preferably made in the form of a mutilated cylinder with one end permanently closed and provided with an offset central chamber 2 for a purpose to be described. The other end of this casing is provided with a hinged closure 3 having suitable means for holding it in detachable engagement with the cylinder, the connecting means here shown being in the form of a spring catch 4 which engages a rib or lug 5 formed on the end of the cylinder, as shown clearly in Figs. 2 and 3. One edge of this closure is cut off as shown at 6, to conform to the shape of the mutilated side of the cylindrical casing. A blade guard 7 is hinged at one edge to the mutilated side of the cylindrical casing and its free edge is preferably made comb-shaped and bent inwardly to engage the lower face of the blade, which is arranged in operative position, as shown clearly in Fig. 4. A spring

7^a is arranged to hold the guard 7 yieldably and closely engaged with the blade when in operative position. The hinging of the guard allows it to move outwardly to permit the successive blades to be brought into operative position when desired. A stop 3^a is preferably arranged on the mutilated edge of the closure 3 to limit the inward movement of the guard, as shown clearly in Figs. 1, 4 and 5. A solid cylindrical member 8 is revolubly mounted in the casing and the axle or shaft 9 thereof is mounted at one end in a suitable bearing formed in the chamber 2, as shown clearly in Fig. 3.

A ratchet wheel 10 is fixed to the shaft 9 and housed within the chamber 2, and is provided with any desired number of teeth 11, said teeth corresponding in number to the number of blades carried by the member 8, six being here shown. A spring 12 is mounted in the chamber 2 and is adapted to engage the teeth of the wheel 10 to hold it against turning in one direction, and which holds the blade carrying member 8 in adjusted position. This blade carrying member 8 is provided in its periphery with a plurality of tangentially arranged sockets 13, the walls of which converge toward their outer end and are designed to prevent the blades from dropping out of the sockets. These sockets 13 extend longitudinally of the member 8 from end to end thereof. A plurality of blades 14, which are wedge-shaped in cross section to correspond with the shape of the sockets 13, are inserted endwise in said sockets with their cutting edges projecting some distance beyond the periphery of the member 8, as shown clearly in Fig. 4. A spring 15, secured to the rear edge of these blades, 95 is preferably constructed in the form shown in Fig. 6, with the ends thereof arranged to bear against the rear wall of its respective socket for holding the blade yieldably in position in said socket with its cutting edge normally projecting in operative position.

The teeth of the ratchet wheel 10 are so proportioned that one of the cutting blades 14 is always arranged in the position shown at A in Fig. 4 when the pawl 12 is in engagement with one of said teeth, and the blade so positioned is ready for use. It will be obvious that any desired number of sockets and blades may be provided accord-

ing to the size of the member 8, six being preferably used, and when one blade becomes dull the member 8 is revolved a distance equal to one tooth on the ratchet 10, 5 which will bring the next blade into the position shown at A in Fig. 4, and cause the dull blade to pass into the casing from which it may be removed at any time by opening the closure 3 and slipping said 10 blade longitudinally out of its socket, but it is not so removed ordinarily until all of the blades are ready to be sharpened, so that one operation will be sufficient. This casing 1 is provided with a suitable handle 16 15 secured to one side thereof in any suitable or desired manner.

From the foregoing description taken in connection with the accompanying drawings, the construction and operation of the 20 invention will be readily understood without requiring a more extended explanation.

Various changes in the form, proportion and the minor details of construction may be resorted to without departing from the 25 principle or sacrificing any of the advantages of the invention, as defined in the appended claims.

I claim as my invention:

1. A safety razor comprising a casing 30 with an opening in one side with a blade guard arranged adjacent said opening, a member revolubly mounted in said casing, a plurality of tangentially disposed blades mounted in said member, and means for 35 holding one of said blades always in operative position relative to said guard.

2. A safety razor comprising a casing having an opening in one side thereof, a blade guard arranged adjacent said opening, 40 a cylindrical member revolubly mounted in said casing, a plurality of tangentially disposed removable blades yieldably mounted in said member, and means for holding one

of said blades in operative position relatively to said guard. 45

3. A safety razor comprising a casing having an opening therein, a member revolubly mounted in said casing, a plurality of tangentially disposed removable blades yieldingly mounted in said member and a 50 blade guard arranged adjacent said opening of the casing with which the blades engage.

4. A safety razor comprising a casing having an opening in one side wall thereof and provided with a blade guard, a solid 55 cylindrical member revolubly mounted in said casing and having a plurality of tangentially disposed sockets in its periphery with the walls thereof converging toward their outer ends, and blades mounted in said 60 sockets with their cutting edges projecting beyond the outer ends of said sockets, said blades being wedge-shaped in cross section, and springs arranged in said sockets in position to bear on the rear edges of said 65 blades to hold them yieldably in operative position.

5. A safety razor comprising a casing having an opening in one wall thereof provided with a hinged blade guard, a blade 70 carrying member arranged in said casing, a blade mounted in said member with its cutting edge projecting through the opening in said casing, a blade guard hingedly connected at one edge to one edge of said 75 casing opening and having its free edge bent inwardly and engaged with one face of said blade, and means for yieldably holding said guard in engagement with said blade.

In testimony whereof I have hereunto set 80 my hand in presence of two subscribing witnesses.

AXEL ANSHELM CARLSON.
